PNEUMATIC DISPATCH CARRIER

Filed Nov. 22, 1929

UNITED STATES PATENT OFFICE

ARTHUR W. SHANNEHAN, OF ROSLINDALE, MASSACHUSETTS, ASSIGNOR TO THE LAMSON COMPANY, OF SYRACUSE, NEW YORK, A CORPORATION OF MASSACHUSETTS

PNEUMATIC DISPATCH CARRIER

Application filed November 22, 1929. Serial No. 408,979.

This invention pertains to carriers such as are employed in pneumatic dispatch systems for transmitting articles or material, for example, cash, charge authorization slips, messages, publications, or merchandise in general, from one station to another and is designed to provide a carrier comprising a plurality of separate compartments facilitating the dispatch in the same carrier of articles or material of different kinds, for instance cash and credit cards or messages.

In the accompanying drawings I have illustrated certain desirable embodiments of the invention by way of example, and in the drawings:

Fig. 1 is a side elevation, partly broken away and in section, illustrating a preferred form of the improved carrier;

Fig. 2 is an end elevation of the carrier of Fig. 1 viewed from the lower end of the latter figure;

Fig. 3 is a transverse section substantially on the line 3-3 of Fig. 1;

Fig. 4 is a view similar to Fig. 1 but illustrating a modified construction;

Fig. 5 is a fragmentary section substantially on the line 5-5 of Fig. 4;

Fig. 6 is a fragmentary section on the line 6-6 of Fig. 4;

Fig. 7 is a view similar to Fig. 1 but showing a further modification; and

Fig. 8 is a fragmentary section illustrating a further modification.

The body of the carrier as disclosed in Fig. 1 comprises an elongate tube 1, preferably of metal, and provided, if desired, near one end with a stop rib 2 which forms an abutment for an annular head 3 of felt or other suitable material which is telescoped over the end of the tube 1 and which is conveniently held in position by beading over the extreme end of the tube, as shown at 4. This annular form of head leaves the end 5 of the tube open to give access to its interior. As shown in Fig. 1 the tube 1 is also provided

with an elongate access opening or window 6 in its side wall and is provided with a resilient retaining clip or spring 7 conveniently secured to the side wall of the tube at the point 8. The free extremity of this resilient clip is disposed opposite to the window 6 and is adapted to hold a paper slip 9 or the like in contact with inner wall of the tube and with a portion of the slip exposed through the window 6. Such slip may be introduced and withdrawn either through the window 6 or through the open end 5 of the carrier body.

The tube 1 is furnished with a second access opening 10 longitudinally spaced from the end of the window 6. A cylindriform or tubular shell 11 is associated with that end of the tube 1 remote from the head 3, such shell 11, as shown in Fig. 1, telescoping within the shell 11 and being free to rotate relative to the latter. This shell 11 extends inwardly to a point intermediate the adjacent ends of the openings 6 and 10 and is there provided with a closure member 12, here shown as a shallow cap fitting within the end of the shell 11 and secured to the latter, as for example by means of solder. This closure 12 forms a partition extending transversely across the tube 1 and dividing the space within the latter into two independent chambers, in one of which is located the spring clip 7 above referred to, while the opening 10 gives access to the other chamber.

The outer end of the shell 11 is closed and provided with a head 13 of felt or the like fixedly secured to the end of the shell, preferably having a driving washer 14 interposed between the head and the end wall of the shell. The shell 11 is furnished with an opening 10^a (Fig. 3) which may be brought into and out of registry with the access opening 10 by relative rotation of the shell 11 and the tube 1, and to prevent relative axial movement of the shell 11 and the tube 1, after the parts are assembled, the shell 11 is provided,

as shown in Fig. 1, with a stop lug 16 removably secured to the shell by means of screws or the like, if desired, and which normally engages an abutment surface 15 defining the end of the opening 10. To permit complete closure of the opening, a recess 17 may be provided to receive the stop 16 when the shell 11 has been turned to closing position.

The carrier thus provided furnishes convenient means for the simultaneous transmission of articles or substances of different character; for example, loose material, such as cash, may be introduced through the opening 10 into one chamber of the carrier and securely retained therein by proper rotation of the closure member 11, while at the same time a charge slip, message, or even small articles of merchandise may be introduced into the other chamber of the carrier and held in position by means of the spring clip 7 or its equivalent. This improved carrier tends to increase the rapidity of service, since it avoids the necessity of sending two carriers in quick succession, although it keeps separate the two classes of material which are to be transmitted.

Referring to Figs. 4, 5 and 6, the modified form of carrier comprises a lower part (as viewed in Fig. 4) which is substantially like the lower part of the carrier shown in Fig. 1, comprising the tubular member 18 having the stop shoulder 2^a, the head 3^a, the window 6^a and the spring clip 7^a corresponding to the parts similarly located in the device of Fig. 1. However, in this instance the tubular member 18 is of a length approximately half the length of the carrier and is furnished with a closed end 19 which forms a convenient anchorage at the point 8^a for the end of the spring clip 7^a. With this tubular member 18 there is associated a second tubular member 20 also having a closed end 21 which is opposed to the end 19 of the member 18, preferably with a driving washer 22 interposed between them, the parts being connected by means of bolts 23 with the members 18 and 21 in axial alignment. The member 20 is furnished with an access opening 24 in its side wall but is open at its upper end, as viewed in Fig. 4 and has associated therewith the cylindriform or tubular shell 25 which, as shown in this figure, telescopes over the outside of the tubular member 20 and extends downwardly nearly to the end 21 of the latter. This shell 25 is provided with an access opening 26 which may be registered with the opening 24 by proper relative rotation of the shell 25 and the member 20, and the outer end of the shell 25 preferably is closed at 27 and has connected thereto the head 13^a and the driving washer 14^a. To keep the shell 25 in assembled relation to the member 20 I prefer to provide the shell 25 with an inwardly projecting stop 16^a which normally engages the abutment surface 15^a at the end of the access

opening 24. To facilitate separation of the parts when desired I provide that portion of the shell 20 which carries the abutment 15^a with a longitudinally extending depressed portion 28, Figs. 5 and 6, forming a channel 29 for the passage of the stop 16^a. To prevent accidental withdrawal of the stop through this passage I provide a spring tongue 30 secured at one end to the depressed bottom member 28 of the channel and having its free end diverging and inclining upwardly with its extremity normally exposed to the stop 16^a. At a point adjacent to the stop 16^a the shell 25 is furnished with a small opening 31 through which a suitable instrument may be inserted to depress the free end of the spring tongue 30 so that when desired the tongue may be moved downwardly into parallel relation to the member 28 to permit passage of the stop 16^a above the tongue.

In Fig. 7 I have illustrated a further modification wherein the upper portion of the carrier may be substantially like that shown in Fig. 4, but wherein that portion of the carrier below the driving washer 22 comprises the short tubular member 18^b having a head or inturned flange 19^b at its upper end by means of which it is secured to the lower end of the upper member of the carrier. This short tubular member 18^b furnishes an anchorage for one end of the tubular member 32 which may be flexible, for example of rubberized fabric, leather, or the like, and which may be secured to the part 18^b by the rivets 33. Near its opposite end the member 32 is provided with the head 34 consisting of a ring of felt or the like suitably secured in position, and the end of the member 32 may be closed by means of a cover 35 secured by a flexible hinge 36 to the member 32 and which may be held in closed position by a snap device 37. Thus in this form of carrier both chambers may be completely closed during transmission of the carrier, although in the arrangement shown in Fig. 7 the contents of the lower chamber are not exposed to view except by opening the cover 35.

Conceivably, as suggested in Fig. 8, one of the carrier compartments may be within the head of the carrier, such head having the cavity 40 provided with a suitable closure or retainer device such, for example, as a flexible strip 41 secured to the bottom of the cavity and having overlapping portions 42 and 43 connected by a snap fastener 44 and adapted to hold a card 45 or the like within the cavity.

While I have illustrated certain desirable embodiments of my invention by way of example, I wish it to be understood that the invention is not necessarily limited to these specific embodiments but that various changes in size, proportion and relative arrangement of parts may be made, that equivalents may be substituted for parts here specified.

cally disclosed, and that the carrier may be provided with a greater number than two of the compartments without departing from the spirit of the invention.

5 5 I claim:

1. A carrier for pneumatic dispatch systems comprising an elongate tubular body, a transverse partition dividing the space within said body into two separate chambers, the 10 body having openings in its side wall giving access to the respective chambers, and independent means for retaining material in each of said chambers.

15 2. A pneumatic carrier provided with a plurality of independent compartments, and independent longitudinally arranged means for retaining material in the respective compartments.

20 3. A carrier for pneumatic dispatch systems comprising an elongate tubular body and having a head adjacent to each end, a transverse partition dividing the space within the body into two distinct chambers, the carrier body having an opening in its side 25 wall giving access to one at least of said chambers, a rotary closure for said opening, the carrier body having an opening giving access to the other of said chambers, and means for retaining material in said latter chamber.

30 4. A carrier for pneumatic dispatch systems comprising an elongate tubular body and having a head adjacent to each end, a transverse partition dividing the space within the body into two distinct chambers, the carrier body having an opening in its side 35 wall giving access to one at least of said chambers, a rotary closure member for said opening connected to one of said heads for actuation by the latter, the carrier body having a constantly open window in its side wall giving access to the other chamber, and a resilient clip within the latter chamber for holding a slip of paper against the inner surface of the body and in display relation to 40 said window.

45 5. A carrier for pneumatic dispatch systems comprising an elongate tubular body and having a head adjacent to each end, a transverse partition dividing the space within 50 the body into two distinct chambers, the carrier body having an opening in its side wall giving access to one at least of said chambers, a rotary cylindriform closure member concentric with the body of the carrier, said closure member being secured to one of the heads for actuation thereby to cover and uncover said opening, the carrier body being open at its other end to give access to the other chamber and having a permanently open window in its side wall opening 55 into said latter chamber, and means in said latter chamber for holding a paper slip therein in display relation to the window.

60 6. A carrier for pneumatic dispatch systems comprising an elongate cylindrical tube

having a fixed head at one end and being open at the other, said tube having an access opening in its side wall, a rotary cylindriform shell fitting within the open end of said tube, a head secured to said shell for rotating the latter to cover and uncover said opening, means to prevent relative axial movement of the shell and tube, and means closing the inner end of the shell and forming a transverse partition dividing the space within the tube into two separate chambers. 70 75

7. A carrier for pneumatic dispatch systems comprising an elongate tube having longitudinally spaced access openings in its side wall, a cylindriform shell concentric with said tube, said shell having an opening registerable with one of the access openings in the tube and being rotatable relatively to the tube to cover and uncover the access opening with which it is associated, means normally preventing relative axial movement of the shell and tube, and means disposed intermediate said access openings forming a transverse partition dividing the space within the carrier into separate chambers. 80 85 90

8. A carrier for pneumatic dispatch systems comprising an elongate tube having longitudinally spaced access openings in its side wall, a cylindriform shell concentric with said tube, said shell having an opening registerable with one of the access openings in the tube and being rotatable relatively to the tube to cover and uncover the access opening with which it is associated, a stop carried by the shell and engageable with the tube normally preventing relative axial movement of the shell and tube, a head fixed to the shell for rotating the latter, a head fixed to the tube, and a partition intermediate the access openings in the tube separating the space in the shell into two separate chambers. 95 100 105

9. A carrier for pneumatic dispatch systems comprising an elongate tube having longitudinally spaced access openings in its side wall, a cylindriform shell concentric with said tube, said shell having an opening registerable with one of the access openings in the tube and being rotatable relatively to the tube to cover and uncover the access opening with which it is associated, a cylindriform shell fitting within the tube and extending from one end of the tube to a point intermediate said access openings, a head fixed to the outer end of said shell for rotating the latter relative to the tube, and a closure for the inner end of the shell forming a partition dividing the space within the tube into two separate chambers. 110 115 120

10. A pneumatic carrier comprising telescopic tubular members, a stop projecting from one member, an abutment on the other member normally engaged by said stop to prevent relative axial movement of the tubular member while permitting relative rota- 125 130

tion thereof, said abutment having a channel through which the stop member may pass to permit axial separation of said members, and a resilient tongue permanently associated with the abutment and disposed in said channel, said tongue normally diverging from the bottom of the channel and having its free end opposed to the stop, said tongue when depressed against the bottom of the channel permitting passage of the stop above it.

Signed by me at Roslindale, Suffolk county, Massachusetts, this fifteenth day of November, 1929.
